UNITED STATES PATENT OFFICE.

EMIL JOSSE, OF WILMERSDORF, GERMANY.

MEANS FOR REGULATING THE PRESSURE IN EVAPORATORS OF COLD-VAPOR ENGINES.

SPECIFICATION forming part of Letters Patent No. 726,433, dated April 28, 1903.

Application filed December 3, 1900. Serial No. 38,388. (No model.)

To all whom it may concern:

Be it known that I, EMIL JOSSE, residing at Wilmersdorf, Germany, have invented certain new and useful Means for Regulating the Pressure in the Evaporator in Connection with Cold-Vapor Engines, of which the following is a specification.

This invention relates to engines worked by means of exhaust heat, in which vapors which are produced by exhaust heat (exhaust steam and exhaust-gases) and boil at a low temperature—for example, ammonia, sulfurous acid, &c.—are employed, these vapors passing out of the evaporator into the cold-vapor engine, being condensed in a condenser and reconveyed to the evaporator in a liquid form in any suitable manner.

The invention consists in the novel arrangement and combination of parts hereinafter described and claimed.

In connection herewith it is desirable to regulate the work of the cold-vapor engine in accordance with the pressure in the cold-vapor generator. If, for example, the cold vapors are produced by the exhaust-steam of an ordinary steam-engine, which in condensing evaporates the easily-boiling fluid contained in the evaporator, then, according to the varying work of the engine, more or less exhaust-steam—in other terms, heat—is conveyed to the evaporator, and therefore also a correspondingly larger or smaller quantity of cold vapor produced in the evaporator. It is, however, desirable in order to utilize the cold vapor advantageously to keep the pressure in the evaporator as nearly as possible at the same degree in order that the power-engine may always have the same force imparted to it when the vapors are admitted.

According to the present invention this is substantially effected by altering the feed of the power-engine when the pressure in the evaporator is too great, while when the pressure in the evaporator is too little auxiliary heat is conveyed to the evaporator from a second source of heat. When the pressure in the evaporator is too great, the operation can be regulated by causing the pressure in the evaporator to act directly on a piston-

slide, diaphragm, or the like, through the motion of which the supply to the cold-vapor engine can be regulated, or it can be regulated by acting directly on the distributing-valves. Should it still happen notwithstanding

ing this that there is too great a pressure in the evaporator when the cold-vapor engine is charged to the maximum, this excess of cold vapors is conducted out of the evaporator directly into the condenser automatically through the medium of a valve. If, on the contrary, too small a quantity of cold vapor is produced in the evaporator, owing to a falling off in the amount of the exhaust-va-
por conveyed to the evaporator, the pressure in the evaporator can be kept constant by furnishing auxiliary heat to the evaporator from a second source of heat—a steam-boiler, for instance—the supply of auxiliary heat being regulated by means of one of the known automatic governors.

The figure of the accompanying drawing diagrammatically illustrates an installation working according to the present invention.

To the evaporator A of a cold-vapor engine B a piston slide-valve C, for example, is connected, which consists, substantially, of a piston a, which moves in a cylinder b. The piston-rod e belonging thereto is connected with a lever d, which effects the turning of a spindle f, situated in the valve-box D of the cold-vapor machine by means of a suitable coupling-rod. The spindle f is connected with the guide-rod h of the cut-off valve g, so that by the action of the piston a the cut-off valve g is simultaneously rotated, whereby the supply to the engine is varied. When, for example, in consequence of a greater quantity of heat more cold vapor is produced in the evaporator and the pressure there increases, the position of the piston a is altered, since it is compressed by a spring i, which is adjustable by means of a screw. By these means the supply to the cold-vapor cylinder is increased—i. e., more cold vapor passes from the evaporator and the pressure in the latter is reduced to its normal. Instead of allowing the motion of the piston a to act on the distributing-valves (in the present case the cut-off valve g) this motion may be employed for operating a throttle contrivance fitted into the cold-vapor-supply pipe. Further, instead of the piston-slide a a diaphragm or the like may be employed.

When the cold-vapor engine is charged to the maximum and owing to the continuous and increased supply of heat the pressure of the cold vapor in the evaporator increases, the excess of cold vapor not taken off by the

engine is discharged directly into the condenser by means of an automatic relief-valve F, located between the evaporator A and the condenser E and weighted by an adjustable spring k. The valve F is connected, through the pipe l, with the cold-vapor chamber of the evaporator A and by the pipe m with the condenser and is controlled by means of the spring k. The tension of spring k is adjustable by means of a screw. When the pressure in the evaporator rises beyond the spring tension of the valve, the latter opens and allows cold vapors to flow out of the evaporator A into the condenser. In the condenser, around which cooling-water is constantly flowing, the cold vapors are condensed in order to be employed afresh. If the pressure of the cold vapors in the evaporator falls below the normal, auxiliary heat is conveyed to the evaporator A from a second source of heat—for example, a steam-boiler—and this supply of auxiliary heat regulated by an automatic governor G.

The fluid to be evaporated passes through the evaporator A through a series of pipes, which are immersed in the exhaust heat, entering at n and escaping at o. Thus it will be seen that what may be termed two "separate" chambers are provided, one for the vapors and the other for the heating medium. The cold vapors under pressure in the evaporator A are conveyed through the pipe p to the cylinder of the pressure-regulator G, in which the piston r of the feed mechanism works. The piston r is subject to the pressure of the cold vapors on one side and subject to the action of a spring q on the opposite side and is connected by a rod with a piston s, which is inserted in a branch pipe u as a shutting-off contrivance. This branch leads from a source of heat—for example, a steam-boiler, the receiver of a steam-engine, or the like—so that if the pressure in the evaporator A becomes too low and the correspondingly-adjusted spring q moves down the combined pistons r and s the piston-slide s allows auxiliary heat to reach the evaporator through the pipe t. If the pressure has again sufficiently increased, the pressure upon the lower side of the piston r will overcome the power of the spring q, and both pistons will resume their former position and the auxiliary heat is shut off.

The arrangement for the automatic regulation of the supply of auxiliary heat may be carried out in any desired manner. For example, the piston r may be replaced by a diaphragm, the piston-slide s by a valve, &c. Furthermore, instead of the springs in the pistons and relief-valves other arrangements—such as weights, weighted levers, or the like—may be employed without departing from the spirit of the invention.

Having described my invention, what I claim, and desire to secure by Letters Patent, is—

1. The combination of an evaporator, means

for admitting heat to said evaporator from a suitable exhaust, auxiliary means for supplying said evaporator with heat and means for automatically controlling the supply from the auxiliary means by the pressure in the evaporator.

2. The combination of an evaporator having a chamber for the vapor and a separate chamber for the heating medium, means for admitting heat to the heating-chamber from a suitable exhaust, auxiliary means in communication with the heating-chamber for conducting an auxiliary supply of heat thereto and means in communication with the vapor-chamber for automatically controlling the flow of heat from the auxiliary means by the pressure in the vapor-chamber.

3. The combination of a cold-vapor engine, an evaporator in communication therewith, a condenser which is likewise in communication with the evaporator and spring-restored means for automatically opening the communication between the evaporator and condenser when the pressure in the evaporator becomes too great.

4. The combination of a cold-vapor engine, an evaporator in communication therewith, means for automatically controlling the supply of cold vapor to the engine by the pressure in the evaporator, means for admitting heat to said evaporator from a suitable exhaust, auxiliary means for supplying said evaporator with heat and means for automatically controlling the supply from the auxiliary means by the pressure in the evaporator.

5. The combination of a cold-vapor engine, an evaporator in communication therewith, means for automatically controlling the supply of cold vapor to the engine by the pressure in the evaporator, a condenser which is likewise in communication with the evaporator and means for automatically opening the communication between the evaporator and condenser when the pressure in the evaporator becomes too great.

6. The combination of a cold-vapor engine, an evaporator in communication therewith, means for automatically controlling the supply of cold vapor to the engine by the pressure in the evaporator, means for admitting heat to said evaporator from a suitable exhaust, auxiliary means for supplying said evaporator with heat, means for automatically controlling the supply from the auxiliary means by the pressure in the evaporator, a condenser which is likewise in communication with the evaporator and means for automatically opening the communication between the evaporator and condenser when the pressure in the evaporator becomes too great.

EMIL JOSSE.
